Inventor

UNITED STATES PATENT OFFICE.

OSMOND THERON BELCHER, OF LOS ANGELES, CALIFORNIA, ASSIGNOR TO BELCHER AERIAL MANUFACTURING COMPANY, A CORPORATION OF CALIFORNIA.

FABRICATED COVERING FOR AEROPLANES.

1,426,626.

Specification of Letters Patent. Patented Aug. 22, 1922.

Application filed July 19, 1921. Serial No. 485,938.

To all whom it may concern:

Be it known that I, OSMOND THERON BELCHER, a citizen of the United States, residing at Los Angeles, in the county of Los Angeles, State of California, have invented new and useful Improvements in Fabricated Coverings for Aeroplanes, of which the following is a specification.

The present invention is an improvement 10 in the structure and in the method of construction of a fabricated wood covering as is set forth in my Patent No. 1,311,205 issued July 29, 1919, entitled "Aeroplane construction," the objects of the present invention 15 being to strengthen the covering and to simplify its method of construction.

With reference to the drawings:

Fig. 1 is a view of a fragment of a simple weave of wood ribbons showing two separate 20 sections of corrugated filler glued upon its surface.

Fig. 2 is a perspective view of a section of corrugated filler used in the covering.

Fig. 3 is a view looking at the edge of a 25 fragment of completed covering.

Fig. 4 is a view of a plurality of corrugated strips used for a filler and showing a method of assembling the filler on rods prior to placing it in the structure of the covering.

30 In carrying out the present invention a simple weave 1 of wood ribbons is made on a special loom. The wood ribbons are sliced from clear stock and for common purposes may be one and one-fourth inch wide and 35 fifteen thousandths of an inch thick. The ribbons are glued end to end and wound on reels for the weaving and form both the warp and weft of the weave. The weave is glued with waterproof glue throughout 40 where the warp and weft lay together.

A sheet of such fabric 1 is laid upon a form which has the shape of a wing or fuselage or other object to be covered and then covered with corrugated strips 2, the strips 45 being set with waterproof glue. A second sheet of the fabric 1 is then placed over and glued down upon the corrugated filler and a top member of the form allowed to rest upon the completed covering until it is sufficiently dried and the glue set thus building up a covering for wings, fuselage and the like which will hold its shape under varying weather conditions.

In the assemblage of the covering and 55 more particularly in placing the corrugated

strips upon the first sheet of fabric some difficulty has been encountered. To illustrate: if the strips 2 are placed as shown at A, Fig. 1, that is with the corrugations matching groove to groove, it has been found difficult 60 to hold the corrugated strips in place while the top sheet is being glued down which practice results in a covering having weakened areas and an uneven surface.

It has been found necessary in the practical manufacture of the covering, to avoid the above mentioned difficulties and weaknesses, in placing the corrugated strips upon the first sheet of fabric to place each strip one-half a corrugation ahead of the preceding one, as shown at B, Fig. 1, that is with the grooves of one strip matching the ridges of the next. This method of construction is followed not only to stagger the convolutions of the filler and strengthen the finished covering but mainly to allow an assembling of the strips 2 on rods 3 in wide sheets, as shown in Fig. 4, the rods 3 being put through a plurality of the strips, over one strip and under the next, as shown, while the strips 75 are held in a proper jig.

Thus a large sheet made up of the corrugated strips may be all hung together with the rods and laid upon a first sheet of fabric which has been placed upon a form and a 85 second sheet of fabric laid upon the corrugations without fear of misplacing them or that they have warped away from a proper position, also with a certainty that all the ridges of the filler will stand up to the same 90 height and all touch and be glued to the overlaying sheet of fabric.

As soon as the second sheet of fabric has been set in glue upon the corrugated filler and the top member of the form let down 95 upon it the rods are then withdrawn, they being made of flexible material so that they can be drawn out from a curved surface, and the finished covering is allowed to dry in the form.

The wood used for fabric and filler may be spruce or of several other varieties. The rods used in assembling the corrugated filler strips may be shaped round or somewhat hexagonal or otherwise and may be of spring 105 brass, aluminum or wood. In assembling the corrugated strips upon the rods it is pointed out that some degree of success may be attained by leaving out some of the rods, for instance by placing into the assemblage 110

every third rod and that the rods need not pass over and under alternate strips but may pass over and under alternate couplets of strips and so on.

5 Having thus described my invention, I claim:

1. In a covering for aeroplanes and the like comprising two sheets of fabricated material having a corrugated filler glued 10 between of the two fabric sheets forming the outside walls of the covering and a corrugated filler formed of narrow strips of a proper material inserted between the two sheets with the ridges of some of the strips 15 of corrugated filler in line with the grooves of other strips of the filler.

2. In a covering for aeroplanes and the like formed of two outer walls of a simple weave of wood ribbons glued in the lap of 20 warp and weft and having a corrugated wood filler glued between, of the two outer fabricated wood walls and a wood filler composed of narrow corrugated wood strips, part of which are positioned with the ridges of 25 the corrugations matching the grooves of the other corrugated strips.

3. A method of constructing a covering of the class described, of laying a first sheet of the fabric described of gluing thereon corrugated strips so arranged that the 30 ridges of one strip match with the grooves of the next and of gluing upon the corrugated strips a second sheet of the fabric.

4. A method of manufacturing the herein described covering of assembling a plurality of corrugated strips upon rods wherein the rods pass under and over alternate strips or sets of strips thus arranging alternate strips or sets of strips with the grooves of one strip or set of strips aligned 35 with the ridges of other strips, whereby a whole sheet of strips is hung together by the rods, of laying a first sheet of the herein described wood fabric, of gluing thereupon the sheet of assembled 40 corrugated strips and of gluing upon the corrugated strips a second sheet of the aforesaid fabric.

In testimony whereof, I have signed my name to this specification.

OSMOND THERON BELCHER.
